UNITED STATES PATENT OFFICE

101,568

DESIGN FOR A COMBINED BACK AND ARM REST FRAME FOR A CHAIR OR SIMILAR ARTICLE

Louis Vavrik, Toledo, Ohio, assignor to The
Hettrick Manufacturing Company, Toledo,
Ohio, a corporation of Ohio

Application August 28, 1936, Serial No. 64,602

Term of patent 14 years

To all whom it may concern:

Be it known that I, Louis Vavrik, a citizen of the United States, and resident of Toledo, Lucas County, Ohio, have invented a new, original, and ornamental Design for a Combined Back and Arm Rest Frame for a Chair or Similar Article, of which the following is a specification, reference being had to the accompanying drawing, forming a part thereof.

In the drawing:

The figure is a rear perspective view of the combined back and arm rest frame for a chair or similar article showing my new design.

I claim:

The ornamental design for a combined back and arm rest frame for a chair or similar article as shown.

LOUIS VAVRIK.
